UNITED STATES PATENT OFFICE.

HENRY T. CRAPO, OF BOSTON, MASSACHUSETTS.

REPRODUCER FOR TALKING-MACHINES.

1,302,140.

Specification of Letters Patent. Patented Apr. 29, 1919.

Application filed January 23, 1918. Serial No. 213,404.

To all whom it may concern:

Be it known that I, HENRY T. CRAPO, a citizen of the United States, residing at Boston, in the county of Suffolk, in the State of Massachusetts, have invented a certain new and useful Improvement in Reproducers for Talking-Machines, of which the following is a specification, reference being had to the accompanying drawings.

10 The immediate object of this invention is to provide simple, but effective, means for use with the needle bar of such reproducers whereby a specially sensitive action is given to the needle as the latter follows the 15 grooves of the record, the said invention briefly described consisting of a novel arrangement of a plurality of permanently magnetized points which act with a cushioning or balancing effect upon the needle bar, 20 in opposition to the vibrating diaphragm.

For the purpose of explaining the said invention clearly, the annexed drawings have been provided, in which the Figure 1 is a plan view of a reproducer embodying the 25 present improvement, looking down upon the vibrator diaphragm needle bar, and Fig. 2 is a transverse, sectional, view of the same taken on the line 2—2 of said Fig. 1. Fig. 4 is a relatively enlarged view of the magnetized spider 15 and of the needle bar located thereunder, and Fig. 3 is a transverse sectional view taken on the line 3—3 of said Fig. 4.

30 Referring to these drawings the numeral 10 indicates the sound box and 11 the vibrating diaphragm mounted in said box in the customary, or any other desired, manner. Journalled in bearings 12 formed on the sound box is the needle bar 13 whose inner 35 end is turned inward and is adapted to engage the diaphragm 11 as the needle bar is vibrated by engagement of the needle with the wave grooves of the record disk.

So far as I am aware the needle bar is 40 customarily free to rock on or in its bearing 12, and is governed as to its movements, solely by the said wave grooves, no provision being made for balancing or cushioning the 45 vibrating action of said needle bar and, by reason of such freedom of the needle and its 50 bar there is an occasional failure on the part of the needle to follow the wave grooves and a blasting or unpleasant sound results.

This objectionable result, I find by re-

peated experiment and demonstration, is 55 overcome by means of my present improved balancing device which I will now describe. Secured to, or formed upon, the needle bar 13, near the inner end of said bar, is a skeleton plate 14, which is here shown as triangular, and fixed to the sound box, immediately over the said triangle, is a circular plate or spider 15 which is formed with inwardly projecting fingers or spurs 16 whose free end portions overlie the triangle 14 and 60 are spaced apart from said triangle one thirty second of an inch or thereabouts. The fingers 16 are permanently magnetized and they therefore operate constantly with a mild tendency to steady the needle bar as 65 to its vibratory movements and to render such movements more reliable thus adding materially to the delicacy and warmth of tonal reproductions, particularly in reproducing quiet or low-toned passages, and 70 also preventing the occasional unpleasant breaks and blasts caused by the needle jumping out of contact with the wave grooves of the record.

It should be particularly noted that the 75 center of the triangle 14 is immediately in register with the center of the inner end portion of the needle bar, and so that the influence of the several magnet points is equalized on the said bar, thus balancing that 80 end of the bar and in no degree tending to cramp it or to rock it laterally. While I have adopted the described triangular form for the plate 14 it will be obvious that a 85 plate of other form could be used with 90 equally good results so long as the magnetic influence is distributed equally around said plate.

The described balancing and steadyng 95 device adds practically nothing to the cost of reproducers yet it improves materially the tonal effects.

Having thus described my invention I claim:—

In a reproducer comprising a sound box, 100 a vibrating diaphragm, and a needle bar whose free end portion is adapted to engage said diaphragm, a plate formed on the said free end portion of the needle bar, a plurality of magnetized spurs located adjacent to 105 said plate and in opposition to the diaphragm.

HENRY T. CRAPO.
